UNITED STATES PATENT OFFICE.

CHARLES H. BOECK, OF JACKSON, MICHIGAN, ASSIGNOR TO THE NOVELTY MANUFACTURING-COMPANY, OF SAME PLACE.

DESIGN FOR A SAD-IRON HEATER.

SPECIFICATION forming part of Design No. 26,302, dated November 17, 1896.

Application filed April 29, 1896. Serial No. 589,608. Term of patent 7 years.

To all whom it may concern:

Be it known that I, CHARLES H. BOECK, a citizen of the United States, residing at the city of Jackson, in the county of Jackson and State of Michigan, have invented a certain new and useful Design for a Sad-Iron Heater, of which the following is a specification.

My invention relates to a design for sad-iron heaters, and especially to a sad-iron heater for use on oil-stoves, gas-stoves, and similar devices.

My invention relates particularly to the sad-iron heater illustrated in the single perspective view in the accompanying drawing, which is stamped from sheet metal.

The leading feature of my design is the heater A, as shown, like an inverted cake-tin

or bake-dish, containing oblong openings A' through the top for the accommodation of the handles of the sad-irons.

The heater is made substantially square or rectangular, with the corners slightly rounded and corrugated.

Having thus described my invention, what I claim is—

The design for a sad-iron heater substantially as described and shown.

In witness whereof I have hereunto set my hand and seal in the presence of two witnesses.

CHARLES H. BOECK. [L. S.]
